UNITED STATES PATENT OFFICE.

CHRISTIAN SECK, OF DRESDEN, SAXONY, GERMANY, ASSIGNOR OF ONE-HALF
TO CARL SECK, OF SAME PLACE.

ROLLER-MILL FOR GRINDING CORN, &c.

SPECIFICATION forming part of Letters Patent No. 253,113, dated January 31, 1852.

Application filed July 9, 1881. (No model.) Patented in Germany November 26, 1880, in England April 13, 1881, in Austria-Hungary June 4, 1881, in Belgium June 21, 1881, and in Italy June 30, 1881.

To all whom it may concern:

Be it known that I, CHRISTIAN SECK, of Dresden, in the Kingdom of Saxony, German Empire, have invented a certain new and useful Improvement in Roller-Mills for Grinding Corn and other Substances, of which the following is a specification.

The improvement relates to that class of grinding-mills in which two rollers revolve in opposite directions with great difference in their circumferential speed.

This improvement consists in the combination, with the rollers and an endless chain for driving them, of novel devices for simultaneously slackening the chain while suddenly removing or shifting the one roller or cylinder from the other to permit any hard substance to pass between them.

In the annexed drawings, Figure 1 is a side view, and Fig. 2 is an end view, of a roller-mill to which the above improvement is applied. Fig. 3 is a diagram showing the way in which the endless chain runs, and showing at the same time the device for slackening the chain and the method of removing or shifting the small roller or cylinder from the larger one. Fig. 4 is a section through the hopper; and Figs. 5 and 6 are detail views upon a larger scale, respectively illustrating the devices for moving one roller away from the other and for slackening the driving-chain simultaneously therewith.

Similar letters of reference designate corresponding parts in all the figures.

The two working rollers or cylinders *d* and *f* are supposed to be of diameters in proportion of five to two. The large roller *d* receives rotary motion by a pulley fixed on its axle. This motion is transmitted by chain *d*², lying or running over the chain-wheel *s* on the axle of *d* to chain-wheel *s*', which is fixed to the axle of the small roller *f*. The diameters of the two chain-wheels *s* and *s*' are such that a circumferential velocity of *d* and *f* is established in the proportion of seven and one-half to one. The two rollers or cylinders rotate in opposite directions, as indicated by arrows in Fig. 3, and in order to impart the proper motion the chain *d*² receives within it the chain-wheel *s*' on the

small roller *f*, and also an idler chain-wheel, *s*², but passes on and engages with one side only of the wheel *s* on the roller *d*. This chain-wheel or idler *s*² turns on an axle carried by a movable lever, as will be specified hereinafter with reference to the purpose of such construction.

In order to remove or to shift the small roller from time to time from the large roller, it is necessary that the chain should allow such movement, and for slackening the chain when the small roller is moved away from the large roller the following arrangement is provided, which is best shown in Fig. 6:

The axle *n* is provided with a handle, *n*', and when it is desired to move the small roller *f* out of engagement with the large roller *d* the shaft is turned slightly by said handle. The turning of the shaft *n* slackens the chain *d*² to permit the shifting of the roller *f*, and simultaneously shifts said roller, as I will now describe. The axle *n* is provided with a crank, *x*. The rod *y*, connected to this crank, passes through the lever *z*, which has its pivot at *z*', and which carries the chain-wheel *s*'. The rod *y* is so connected to the lever *z* that if axle *n* is turned the partial rotation of crank *x* will lift the lever *z* and the wheel *s*', so that the chain becomes slackened. The upper end of the rod *y*, which passes beyond lever *z*, is surrounded by a spiral spring, *s*³, the upper end of which rests against a nut and a counter-nut on the thread applied to the uppermost end of the rod *y*, and which spring, with its lower end, rests on the lever *z*.

The shifting of the roller *f* is caused by the cranks *w*, fixed at the end of the axle *n*. The plumber-block *v*, surrounding the pin of crank *w*, will, if the crank is turned, push against the lower end of the rod *u*, which in its upper part is connected to the lever *t*. This lever forms an angle and is fulcrumed at *k*, and is provided with bearings *g* for the small roller or cylinder.

It will follow from the arrangements described above that if axle *n* is turned the two motions will be produced simultaneously, viz: Slackening of the chain by the parts: crank or eccentric *x*, rod *y*, and lever *z*, which carries

the chain-wheel s^2 ; and shifting of the small roller by the parts: crank-pin w , plumber-block v , rod u , and lever t .

In order to regulate the exact position of small roller f with reference to large roller d , the hand-wheel l is used, which forms the female screw-nut to the screw-thread on the rod u . i is a jam-nut for securing the exact position. A second screw, m , provided with two nuts, may be used for the same purpose, as seen in Fig. 1.

Referring now more particularly to Fig. 5, through rod u a wedge, u' , is driven, upon which the plate u^2 rests. The two rods $u^3 u^4$, connected to the block v , extend in upward direction, and are connected together at the upper end by plate u^4 , which is loose on the rod u . Between plate u^2 and plate u^4 a spiral spring is arranged, surrounding rod u . By this arrangement of parts the attendant is enabled to regulate the exact position of roller f , and at the same time to shift the roller f , if this becomes necessary, for the passage of a hard body or bodies between the two grinding-rollers.

It will be understood from the foregoing that the crank-pin w , acting through the rods u^3 , the plates $u^2 u^4$, and the spiral spring surrounding the rod u , holds the roller f against the roller d with a yielding pressure, while when the block v strikes the lower end of the rod u the roller f is moved positively away from the roller d . In the same way the crank x exerts its force on the lever z through the spiral spring s^3 , and therefore holds the said lever and the idler-wheel s^2 , which it carries, down with a yielding pressure.

On the axle of the small roller or cylinder f a chain-wheel, s^4 , is situated, which communicates rotary motion by means of a small endless chain, s^5 , to the feeding-roller r . This roller carries at one end a crank, r' , the pin of which works in the slot of the lever r^2 . This lever is fixed to the outer end of an axle, r^3 , situated horizontally in the hopper. This axle is provided with one or more fingers, r^4 , which by the described arrangements of parts receive a swinging or reciprocating motion, by which any obstruction of the material in the hopper and stoppage of the feed of material to the rollers are prevented.

What I claim as my invention, and desire to secure by Letters Patent, is—

In a roller-mill, the combination of two rollers, a chain for transmitting motion from one to the other, pivoted levers comprising bearings for one of said rollers, a chain-wheel or idler, around which said chain is passed, and a lever comprising bearings therefor, and a shaft and connections whereby said levers may be simultaneously raised to remove one roller from the other and for slackening said chain, substantially as specified.

In testimony whereof I have hereunto set my hand, this 20th day of May, 1881, in the presence of two subscribing witnesss.

CHRISTIAN SECK.
